[57] CLAIM

The ornamental design for a windshield visor for trucks, as shown and described.

DESCRIPTION

FIG. 1 is a perspective view of a windshield visor for trucks showing my new design, it being understood that the broken lines are for illustrative purposes only;

FIG. 2 is a top plan view thereof;

FIG. 3 is a front elevation view thereof;

FIG. 4 is an elevation view taken from one end thereof;

FIG. 5 is an elevation view taken from the opposite end thereof;

FIG. 6 is a bottom plan view thereof;

FIG. 7 is a rear elevation view thereof; and,

FIG. 8 is a vertical section view taken substantially along line 8—8 of FIG. 7.

FIG. 4

FIG. 5

FIG. 6

FIG. 7

FIG. 8
